Herman C. Kalwitz, Park Ridge, Ill.

Refiled for forfeited application Serial No. 559,358,
August 26, 1931. This application May 11, 1933,
Serial No. 670,430

11 Claims. (Cl. 200—48)

This application is a continuation in part of my copending application that has now issued as Patent No. 1,944,661, and a substitute for my application, Serial No. 559,358, filed August 26, 1931.

5 The present invention relates to electric switches in general and more particularly to such switches as are used on high, or moderately high, voltage systems and are contained in a suitable housing. While the present invention is particularly applicable to enclosed type disconnect switches it is not limited thereto, being also applicable to other types of disconnect switches, or to high voltage switches in general, such as circuit breakers or the like.

10 It is one of the objects of the present invention to provide a switch which will afford a high degree of safety to people working on apparatus connected therewith. I accomplish this end by providing a grounded barrier which is arranged to move between the two switch terminals when the switch is opened. By this arrangement the switch contacts may be placed closer together without sacrificing on the safety factor.

15 In disconnect switches of the type enclosed in a suitable housing or casing the barrier may be utilized to give a visual indication of the open or closed position of the switch. It is a familiar rule with power operating companies that no man shall work on an oil circuit breaker unless he can actually see the disconnect switch in such position as to interrupt the continuity of the proper line conductor. When such switches are placed in a housing or casing the workman can never feel sure that the switch is in such position as to guarantee safety, notwithstanding the fact that the usual indicating means external of the casing indicates such position. The more mechanism there is interposed between the indicator and the switch blade or member that actually

20 closes the gap between the terminals of the switch the greater is the probability that a false indication may be given due to some of the interposed apparatus failing to function properly. This has always constituted a source of danger to operating men. In accordance with the teachings of the present invention this danger is eliminated by mounting the barrier directly on the switch blade support within the casing so that the barrier moves with the switch blade.

25 Two aligned windows are provided in the switch housing and the arrangement is such that the grounded barrier obstructs light from passing through both windows when the switch is moved to its closed position, whereas it permits light to

30 pass through both windows when the switch is

35 moved to its open position. If the barrier is in the way between the two windows, no light can shine through and the attendant therefore knows that the disconnect switch is closed. If light does shine through, the attendant thereby knows that the barrier is out of the way and the disconnect switch is open so that the oil circuit breaker is disconnected. If the disconnect switch is immersed in a bath of insulating oil which is relatively discolored or otherwise not clear, an electric light may be placed on the outside of and adjacent to one of the windows.

40 In accordance with the teachings of my invention opening of the switch results not only in an interruption in the electrical continuity of the conductor but also in a division of the oil chamber into two compartments wherein any potential above ground that may exist in one of the compartments cannot possibly be carried over to the other compartment. The grounding barrier 45 that is interposed between the two terminals provides a physical separation of the continuity of the sheath or casing within which the switch is located. At points where a grounding barrier cannot be maintained I interpose an insulating 50 barrier. By this arrangement I positively preclude any possibility of a workman inadvertently poking a screw driver or other object beyond the confines of the portion of the sheath or housing within which he is working, and toward the other 55 portion. In addition, I provide means for positively placing ground potential on the contact bar when the switch is open. Thus the contact bar, which extends between the two portions of the switch casing, cannot possibly be at any potential other than ground potential when the switch is open.

60 It is further object of my present invention to provide an improved switch wherein electrical connection may be made with great facility and 55 wherein the line circuit extending from the switch may be by-passed when the switch is open for inspection or repair purposes.

65 The attainment of the above and other objects of the present invention will be apparent from 50 the following specification taken in conjunction with the accompanying drawings forming a part thereof.

In the drawings:

Figure 1 is a transverse sectional view through 50 one bay of a switching station wherein my improved switches are employed;

Figure 2 is an enlarged vertical transverse section through the switch;

Figure 3 is a horizontal section taken along 55

the line 3—3 of Figure 2 and looking in the direction of the arrows;

Figure 4 is a vertical transverse sectional view through a modified form of switch embodying the principles of my invention;

Figure 5 is a sectional view taken along the line 5—5 of Figure 4;

Figure 6 is a fragmentary sectional view illustrating another embodiment of my invention;

Figure 7 is a fragmentary view of a portion of the top of the switch shown in Figure 6; and

Figure 8 is a fragmentary view illustrating the application of a photoelectric cell to a switch of my invention.

15 In the following detailed specification like reference numerals refer to like parts throughout.

Reference may be had first to Figure 1. A main bus is indicated at 1 and a transfer bus at 2, both of the buses consisting of longitudinal conductors extending lengthwise of the station. These buses are adapted to be connected to a power conductor 3 which may be an incoming or an outgoing line. The main bus 1 is adapted to be connected to the conductor 3 by means of a 20 pair of disconnect switches, one of which is indicated at 4, and an oil circuit breaker 5. The transfer bus is adapted to be connected to the line 3 by means of an oil circuit breaker 6 and a pair of disconnect switches, one of which is indicated at 7, and connects one pole of the circuit breaker to the line 3. The particular way in which the connections are established will be more fully set forth as this description proceeds. For a further description reference may be had 25 to the parent patent as set forth above. The three conductors comprising the main bus and the three conductors comprising the transfer bus are disposed each in a separate metallic tubular sheath, each sheath being provided with a metallic junction box such as is indicated at 10, at the point where the connection is to be made to the conductor within. The tubular sheaths within which the conductors are disposed are preferably thin copper pipes or the like, and the boxes 30 10 are preferably thin cast iron boxes. They may be of any form of sheet metal or of cast metal such as bronze, aluminum, non-magnetic iron, or any suitable medium, preferably of a non-magnetic character.

50 The junction box 10 for the bus 1 rests upon a similar box or casing 11, there being a metallic wall 12 common to the two boxes. A bushing type insulator 13 extends through this wall and provides insulation for the tap which extends 55 from the conductor, through the bushing, to a stationary terminal 14 of the disconnect switch 4. The terminal 14 is mounted upon a block 16 of insulation, and a similar terminal 18 is likewise mounted upon a block of insulation 19 within 60 the casing 11, these insulating blocks preferably being supported upon the bottom wall of the casing 11. The casing 11 has an upwardly projecting extension 20, which is more clearly shown in Figure 2 and which will be more fully 65 described as this description proceeds.

The casing 11 has a flange at 25 to which an oil circuit breaker terminal box 26 is adapted to be clamped by a cooperating flange. This box 70 26 is generally rectangular, although the form of the same is optional. At its bottom it has a clamping flange 27 to which a flange of a suitable collar 28 is clamped. Suitable cap screws or the like are employed for joining these two flanges. The bottom of the collar 28 likewise has

a clamping flange which is coupled to a flange forming a part of the circuit breaker frame. This last mentioned flange is formed on a sleeve 29, the lower end of which forms a part of the top frame of the circuit breaker.

5 The sleeve 28 surrounds a terminal bushing 30 of the circuit breaker, the terminal bushing being a permanent part of the circuit breaker structure. The bushing extends upwardly into the box 26 and supports a terminal 31 which is a permanent part of the circuit breaker. To the terminal 31 a conductor 32 is connected, thereby establishing a connection between the terminal 18 of the disconnect switch 4 and one side of the circuit breaker.

10 The circuit breaker 5 has, of course, two terminals, as is well known to those skilled in the art, mounted upon the top frame of the same. The second terminal is identical to that above described and is located immediately in the back 15 of the bushing 30. This terminal is connected, through a disconnect switch similar to the switch 4 and located immediately in back of the same, to the conductor 3. The connections between this side of the circuit breaker and the conductor 3 are 20 identical to the connections between the circuit breaker 6 and the conductor 3, as illustrated at the left hand side of Figure 1.

25 The bushing 30' of the oil circuit breaker 6 affords a connection to the terminal 18' of the 30 disconnect switch 7. This connection is identical to the connection through the bushing 30 to the terminal 18, as previously described, and similar parts have been indicated by similar reference numerals which, in connection with the circuit breaker 6, are primed.

30 A conductor 35 extends the circuit from the terminal 14' of the disconnect switch 7, said conductor extending through an opening in the end wall of the casing 11', through an oil barrier 36 40 and a tube 37 into a box or casing 38 which forms a junction between the conductor 35, extending from one side of the circuit breaker 6, and a corresponding conductor correspondingly extending from the side of the circuit breaker 5 opposite to 45 that illustrated in Figure 1.

35 The conductor 35 is connected to the line conductor 3 at 40 where the line conductor passes through an insulating bushing 41. The bottom of the junction box 38 has a short flanged nipple 42 bolted thereto with the upper end of the bushing 31 projecting into the casing 38. The other end of the flanged nipple 42 is bolted to the top of a current transformer casing 43 and the lower end of the bushing 41 projects thereinto. 50 A current transformer 44 of the removable type, that is, it has a main conductor, the end of which may be clamped to the adjacent conducting parts so that the entire transformer may be readily removed, is mounted in the casing 43. The current transformer conductor extends through a suitable bushing 46 into a terminal box 47 where connection is established to the line 3.

55 The disconnect switches 4 and 7 are of identical construction and are illustrated more particularly in Figures 2 and 3.

60 The extension 20 which is mounted upon the terminal box 11 forms a liquid-tight seal therewith and constitutes a continuation of the box 11 to provide a housing for an operating rod 50 70 and a barrier 51. The extension 20 extends the full width of the casing 11 and is provided with a cover 52 having a collar 53 constituting a bushing through which the operating shaft 50 may move while maintaining a liquid-tight seal.

The rod or operating link 50 supports at its lower end, a switch link or bar 55 carrying contacts 56 and 57 at its ends adapted to cooperate with the spring contact fingers 14 and 18 mounted upon the terminals that are supported by the insulators 15 and 19, as previously set forth. The switch bar 55 is a conducting link which is removable from the contacts 14 and 18 to physically and electrically interrupt the continuity of the circuit extending between them.

The disconnect switch bar 55 is adapted to be thrust downwardly into the position shown in Figures 2 and 3 to disconnect the circuit extending to the corresponding pole of the circuit breaker 5 shown in Figure 1. The opposite pole of the circuit breaker 5 is provided with a disconnect switch corresponding to the disconnect switch 7 of Figure 1 and similarly connected for opening that side of the circuit breaker.

The barrier 51 comprises a metallic plate 60 preferably, but not necessarily, completely covered with insulation except at its edges by an envelope 61 of insulation, and this metal plate 60 is guided in suitable guideways 63 and 64 formed at the sides of the casing. This is clearly shown in Figure 3. The barrier 51 is intended to interpose between the disconnect terminals a grounded metallic barrier for insuring workmen against injury during any work upon the oil circuit breakers or in connecting or disconnecting them. The lowering of the disconnect bar 55 is accompanied by the interposition of the grounded barrier between the terminals 14 and 18, this barrier being grounded through the casing and the guideways such as 63 and 64. In fact, the metallic plate 60 may be connected by a flexible lead to the grounded casing so as to insure not only that the disconnect switch is open but also that a grounded barrier is interposed between the live parts and the parts which are intended to be rendered dead by the opening of the disconnect switch.

The barrier 51 is adapted to enter the housing 20 when the disconnect switch is closed. Aligned sight openings 65 and 66 are provided upon opposite sides of casing 20. These sight openings have glass windows 67 and 68 held in place by clamping rings 69 with suitable interposed gaskets to seal the sight openings. The barrier 51 performs the additional function of providing an indicator for indicating the open or closed position of the disconnect switch. That is to say, when the barrier is lowered, an operator or an attendant can look through the two windows and see that the switch is open. If the oil is relatively discolored or otherwise not clear, an electric light may be placed on the outside of and adjacent to one of the windows to determine whether or not the barrier is located between the two windows. If the barrier is in the way no light can shine through and the attendant therefore knows that the oil circuit breaker is not fully open, or is closed. If the light shines through and may be seen from the opposite window the attendant is thereby apprised of the fact that the barrier is out of the way and the disconnect switch is open, so that the oil circuit breaker may be physically removed or worked upon.

Where it is desired to employ the disconnect switch of my invention for sectionalizing cable, the two ends of the casing 11 are provided with glands for wiping joints to the sheath of the cable. I do not wish to be limited to putting the cable connections at the ends, as the casing 11 may be provided with suitable openings for the connection of the cable ends at either the sides or

the ends of the housing 11. The cable may be a single phase or multi-phase cable, and where multi-phase cable, such as three-phase cable, is to be sectionalized, the housing 11 may be a unitary housing for a number of disconnects, suitably separated by barriers, and the operating mechanism for all three phases may be suitably connected together. Such disconnect switches may be placed under ground or, in fact, in any position in which cable or other apparatus may be located, without danger of the same becoming grounded through moisture or the like, and with the assurance of safety for the workmen. Instead of employing the packing gland 53 for the stem 50 of the disconnecting switch, a metal expandable bellows may be employed for maintaining at all times hermetically sealed joints.

The switch shown in Figure 4 is mounted within a casing 100 to the opposite end of which are welded terminal boxes 101 and 102. The current carrying conductors extend into the casing 100 by way of bushings 103 and 104 which are bolted to the end walls of the casing 100 and form liquid-tight seals therewith. The terminal boxes 101 and 102 have circular openings in their tops, bottoms and sides for extending circuit connections. In the case of the terminal box 101 the bottom and side openings are closed by plates 106 and 107 that are suitably gasketed and bolted to form a liquid-tight seal. A pot-head body 108 is secured to the upper opening in the terminal box 101 and extends a line conductor 109 to the terminal of the bushing 103. In a like manner, plates 110 and 111 are suitably bolted to the top and bottom openings of the terminal box 102, and a pot-head body 112 is secured to the side opening of this box and extends a conductor 114 to the bushing 104. The various openings in the terminal boxes 101 and 102 are of the same sizes, so that the pot-head body may be used to extend the circuit to the switch through any of the openings, depending upon the direction of the incoming or outgoing line conductors. The conductor 109 extends the circuit through the bushing 103 to a terminal 115 from which a male plug type contact 116 extends upwardly. A flexible lead conductor 117 is clamped to the terminal 115 and extends the circuit to a switch contact 118 mounted on an insulator 119 that is mounted on the under side of a cover plate 120 of the casing 100. The cover plate 120 is bolted in place by means of a number of bolts and wing nuts indicated at 120a.

The conductor 114 extends the circuit to a terminal 115' and to a switch contact 118' which is mounted on an insulator 119' that is bolted or otherwise secured to the under side of the cover 120. The leads 117 and 117' may be removed from the terminals 115 and 115' by loosening the respective nuts that hold them in place.

The cover 120 is provided with openings immediately above the respective male plug type contacts 116 and 116', said openings being closed by removable closure members 121 and 121' that are suitably gasketed to form liquid-tight seals.

A switch blade 125 is mounted on an insulating rod 126, which is bifurcated and through which extends a metallic grounding plate 127 the lower edge of which terminates at a safe distance from the blade 125. An insulating plate 128 extends from the lower edge of the plate 127 into proximity with the blade 125. When the switch is open the blade 125 rests upon spring contacts 130 and 131 which maintain ground potential upon the blade. To close the switch the grounding plate

127 is drawn upwardly, thereby bringing the switch blade into contacting relation with the switch contacts 118 and 118'. Actuation of the switch is accomplished through a rotary shaft 5 135, a crank 136 and a link 137 which connects the crank with the plate 127. The grounding plate 127 moves within an extension 139 that is welded to and extends the full width of the casing 100, forming a liquid-tight seal therewith. This cor-
10 responds to the extension 20 of Figure 2.

In this switch, as in the switch shown in Figure 2, the grounding plate 127 terminates between the lower edges of two aligned windows 141 and 142 when the switch is open. When the switch is closed the plate moves between the windows.

If it is desired to remove the cover, for inspection or repair purposes, the closure caps 121—121' are removed to gain access to the leads 117 and 117', and these leads are removed from the plugs 116 and 116'. Thereafter, upon loosening of the wing nuts 120a, the entire cover 120 may be removed, said cover carrying with it the insulators 119—119', the terminals 118—118', and the switch blade and the supporting means therefor.

25 The switch shown in Figure 4 may be a single phase switch, as is the switch shown in Figures 2 and 3, or it may be a polyphase switch. In the present embodiment I have illustrated the same as a polyphase switch, comprising four separate 30 side by side switches. This is illustrated in Figure 5. The respective switch rods are all mounted upon the same barrier plate 127. The switch units are separated from one another by barrier plates 141 that extend across the casing 100 at right 35 angles to the barrier 127 and are slotted to extend on the opposite side of the barrier 127.

When the switch is opened the springs 130 and 131 constitute rebound springs for breaking the fall of the switch blades and associated parts. 40 These springs also constitute ground contacts for the switch blades.

If it is desired to extend a circuit connection to or from the plug 116 or 116', it is merely necessary to remove the corresponding closure cap 121 or 121' and establish connection with the plug. This may be accomplished by inserting, into the opening above the plug, an insulating bushing which carries at its lower end a female contact that establishes electrical connection with the plug 116 or with the plug 116'. Thus, if the conductor 109 constitutes an outgoing line it is possible to maintain service on this line even when the switch is open, this being accomplished by plugging a line connection to the male plug 116. The left hand half of the disconnect switch is then alive, whereas the right hand half is at ground potential and may be worked upon with safety. This same procedure may, of course, be followed for extending a circuit to the conductor 114 by way of the plug 116'.

Reference may now be had to Figures 6 and 7, wherein I show a modified form of switch structure. In this embodiment of my invention the circuit from the conductor extending through the bushing 103 is brought to the switch terminal 118 by means of a switch blade 150 that is carried at the end of the bushing 103 and cooperates with pronged contacts 151 that are carried by a proper bracket 152 at the bottom of the insulator 119. Similar connections are established from the conductor that extends through the bushing 104 to the right hand switch terminal 118'. This arrangement eliminates the necessity of the flexible leads 117 and 117'. In this arrangement when the cover is removed it may be lifted

bodily upward without previously disconnecting leads such as 117 and 117'. When the cover of this switch housing is lifted the insulators 119 and 119' carry the brackets 152 and 152' upward whereby the pronged contacts 151 and 151' are moved out of engagement with the respective knife terminals 150 and 150'. 5

In the switch shown in Figure 6 the side wall 160 constitutes a portion of the cover, said side wall being bent over to form the portion 161. 10 Likewise, the opposite side 162 of the switch is also integral with a portion of the cover as indicated at 163. The portions 161 and 163 are provided with circular holes above the respective male plugs 116 and 116', which circular holes 15 are closed by suitable closure plates 164 and 164'. The inner peripheries of the openings above the plugs 116 and 116' are upwardly flanged, as indicated at 165, and the inner edges of the top portions 162 and 163 are also upwardly flanged, as 20 indicated at 168. The removable cover 120' extends between the upwardly flanged portions 168-168 and beads over those flanges to form a liquid-tight seal. Suitable bolts 170-170 serve to lock the cover plate 164-164 in place and 25 likewise serve to hold the cover 120' in place.

From my above description it is apparent that I have invented an improved switch having a degree of safety and flexibility which is highly desirable. Should an operator be unable to look through the windows on the opposite sides of the upwardly projecting extension 20 or 139, he is thereby warned that it is not safe to work upon the switch. If the oil becomes foggy, this will indicate danger, rather than safety—a highly desirable characteristic. Also, the barrier plate is so located that if it is not between the two windows, as is evidenced by light shining between the windows, it can be nowhere else than between the switch contacts, and the operator is thereby apprised with certainty that the switch is open.

In Figure 8 I have shown the application of a photoelectric cell to a switch such as is shown in Figure 2, it being obvious, from Figure 8, that the same is applicable to the switch shown in Figure 4. A housing 80, pivoted at 81, contains an incandescent electric lamp 82, which may be supplied with energy from any suitable source. Light from the incandescent lamp 82 shines through the window 67 and, if the barrier 60 is in its lowered position, through the window 68, and strikes a photoelectric cell 84. The photoelectric cell 84 is mounted in a housing 85 pivoted at 86. The circuit of the photoelectric cell 84 includes a signal 87 which may be either a visual or audible signal, that is, either an electric light or a buzzer, or the like. A short circuiting switch 88 is provided for the signal 87. The circuit for the photoelectric cell 84 extends by way of the conductors 89 and 90 to a source of electrical energy and to a signal which may be mounted on a switch board at some remote point. When the disconnect switch is in its open position the signal 87 will be energized and thereby give a continuous indication of the switch open position. Should the light 82 fail, or should any defect develop in the signaling circuit, the resulting deenergization of the signal 87 will indicate danger. Therefore, as long as the signal 87 is operative the attendant knows that the disconnect switch must be in its open position and that it is safe to work upon the circuit.

In compliance with the requirements of the patent statutes I have herein shown and described 75

scribed a few preferred forms of my invention. It is, however, to be understood that the invention is not limited to the precise construction herein shown, the same being merely illustrative 5 of the principles of the invention.

What I consider new and desire to secure by Letters Patent is:

1. A disconnect switch comprising a pair of terminals mounted in insulated relation, a housing for the switch enclosing said terminals, a connecting bar for the terminals, a supporting member for the bar, and a grounded barrier carried by the supporting member between the terminals, said disconnect switch housing having 10 an extension into which the barrier moves when the switch is closed, said extension including a pair of aligned openings through which light may pass only when the barrier is in substantially its full open position, said barrier in its 15 other positions obstructing the light path between said openings.

2. In a switch mounted in a switch housing, means for indicating the open and closed position of the switch, said means comprising a pair 20 of aligned windows for permitting light to be directed through the housing, and a barrier in the housing obstructing said light and moved out of obstructing position as the switch reaches its open position, the edge of the barrier being adjacent 25 the line of sight between the windows when the switch is open whereby the sight path is obstructed responsive to the initiation of the switch closing movement.

3. A switch comprising a casing having top, 30 bottom and side walls defining an oil tank, insulators within the casing, contacts mounted on the insulators, bridging means movable into and out of bridging relation to the contacts, a grounding plate carried by the bridging means and insulated 35 therefrom, the casing having a slit-like opening within which the plate moves as the bridging means is moved between its switch closed and its switch open positions, and, separate 40 from the casing, an enclosure surrounding the slit-like opening and secured to the casing and forming a liquid tight seal therewith, said 45 enclosure having a pair of aligned windows between which the grounding plate moves, said plate being adjacent to but clearing the line of sight between said windows when the bridge member reaches substantially its full open position and said plate moving into vision obstruction 50 position between the windows upon the initial movement of the bridge member from its full open position towards its closed position.

4. A switch comprising a casing having top, bottom and side walls defining an oil tank, insulators within the casing, contacts mounted on the 55 insulators, bridging means movable into and out of bridging relation to the contacts, an insulating actuating rod connected to the bridging means, a grounding plate carried by the rod and insulated from the bridging means, the top of the casing having a slit-like opening within which the rod and the plate move as the rod is moved between its switch closed and its switch 60 open positions, an open bottomed enclosure surrounding the slit-like opening and secured to the casing and forming a liquid-tight seal therewith, the top of said enclosure being closed, and said rod extending through said enclosure and moving within an opening in the top and filling said opening, said enclosure having a pair of aligned 65 windows between which the grounding plate

moves, said plate being adjacent to but clearing the line of sight between said windows when the bridge member reaches substantially its full open position and said plate moving into vision obstruction position between the windows upon the initial movement of the bridge member from its full open position towards its closed position. 5

5. A switch comprising a casing having a removable cover, a switch structure supported therefrom and including insulators, switch terminals mounted on the insulators, a switch blade for establishing connections between the terminals, a barrier plate conjointly movable with said blade into a vertical plane between the terminals, conductors, insulators projecting normal to 10 said first named insulator for extending the conductors into the casing, terminals terminating the conductors at points spaced from said switch terminals and switch means operable upon closure of said cover over said casing for establishing 15 electrical connection between said last mentioned terminals and the switch terminals.

6. A switch comprising a casing having a removable cover, a switch structure supported therefrom and including insulators, switch terminals mounted on the insulators, a switch blade for establishing connections between the terminals, conductors, insulators extending the conductors into the casing independently of said removable cover, terminals terminating the conductors, and switching means including portions connected to the switch terminals and portions connected to the last mentioned terminals and, closed by closure of the cover for establishing an electrical connection between said last mentioned terminals and the switch terminals. 25

7. A switch including a casing, insulated conductors extending into the casing through the walls thereof and terminating in switching terminals, a cover for the casing, said cover carrying a pair of terminals and means for connecting and disconnecting the cover carried terminals, and additional means carried by the cover for connecting the cover carried terminals to the first mentioned terminals upon closure of the cover on 30 the casing. 40

8. A switch comprising a casing, a terminal box at each end thereof, conductors extending into the casing through insulators providing a liquid-tight seal, terminals mounted on the respective conductors within the casing, openings in the casing wall opposite the terminals for extending circuit connections to the terminals, closures for the respective openings, switch terminals in the casing and connected to the first mentioned terminals by a removable connection, separate insulators supporting the last mentioned terminals, and a switch blade movable into and out of circuit closing position between the two last mentioned terminals. 50

9. A disconnect switch comprising a casing, conductors extending into the casing from the opposite ends thereof said conductors terminating in said casing substantially in longitudinal alignment, a pair of insulators mounted in said casing and extending laterally of the conductors, terminals on the insulators spaced from and substantially in alignment with the conductors, means for connecting said conductors to said terminals, a switch blade bridging the terminals and substantially in alignment with the conductors, said blade being gravity biased to the switch open position, a grounded barrier plate connected to the blade but insulated therefrom and movable 65 70 75

between the terminals when the blade moves to its switch open position, guides at the opposite sides of the casing for guiding the plate, and grounding contacts engaging the switch blade 5 when the blade is in its open position, said grounding contacts being mounted on leaf spring means constituting cushioning springs for the blade.

10. In combination, a switch housing, a pair of conductors extending into said housing, contact blades carried by and projecting from said conductors, a detachable cover for said housing, insulators carried by said cover, a pair of offset spaced contact clips carried by each of said insulators, one of each of said pair of clips engaging 15 said contact blades when said cover is positioned upon said housing, a switch bar for bridging across said other contact clips, and operating means for said bar including a grounded barrier plate member within said housing movable in a 20 vertical plane into position between said insulators for dividing said housing between said insu-

lators when said switch bar is in switch-open position.

11. A switch structure comprising a housing disposed between the adjacent ends of two conductor sections, insulators extending the conductors into the opposite ends of said housing, switching terminals on the ends of said conductors in said housing, a cover for said housing, a pair of depending insulators carried by said cover, switching means carried by said depending insulators and engageable with said switching terminals upon closure of said cover, a switch operating mechanism carried by said cover, a switch operated thereby within said housing, switch contacts carried by said depending insulators engaged by said switch in switch closed position, and means in said housing for cushioning the switch-opening movement of said switch away from said contacts. 5 10 15
